(57) **CLAIM**

The ornamental design for a shell casing deflector, as shown and described.

DESCRIPTION

FIG. 1 is a left front perspective view of a shell casing deflector showing my new design;

FIG. 2 is a front elevation view thereof;

FIG. 3 is a rear elevation view thereof;

FIG. 4 is a top plan view thereof;

FIG. 5 is a left side view thereof;

FIG. 6 is a right side view thereof; and,

FIG. 7 is a bottom plan view thereof.

The dotted line portion is for reference purposes only and forms no part of the claimed design.
